MOLD DISK DRIVING MECHANISM FOR
TYPOGRAPHICAL CASTING MACHINESPaul Hilpman, Garden City, N. Y., assignor to
Mergenthaler Linotype Company, a corporation
of New York

Application July 19, 1950, Serial No. 174,647

6 Claims. (Cl. 74—435)

1

This invention relates to typographical casting machines, such as Linotype machines of the general organization represented in Letters Patent of the United States to O. Mergenthaler, No. 436,532, wherein a composed line of matrices is presented to the face of a mold carried by a rotatable disk, the mold filled with molten metal to form a type bar or slug against the matrices, and the slug thereafter ejected from the mold and trimmed.

The rotative motion is imparted to the mold disk through an arrangement of gears driven by a large mold turning wheel (often referred to as a cam). The mold turning wheel carries on its circumference a short and a long gear segment, adapted to mesh with and rotate a bevel pinion, the short segment serving to rotate the mold disk through a one-quarter turn from the slug ejecting to the slug casting position, and the long segment serving to rotate the disk through a three-quarter turn from the slug casting to the slug ejecting position. The location of the mold in the slug casting and slug ejecting positions is critical and, therefore, after each of the partial rotations, the mold disk is brought to a stop by a friction brake and moved bodily to cause the locking studs thereon to enter a pair of banking blocks on the vise frame in order to effect accurate alignment in each position. However, in order to prevent excessive wear on either the mold disk locking studs or the banking blocks, it is necessary to locate the mold disk as accurately as possible beforehand. For this purpose, a square block is situated directly behind and on the same shaft with the bevel pinion, there being very little clearance between the sides of the mold turning wheel and said block. During the rotation of the shaft by one of the gear segments, there is sufficient clearance provided to permit the locating block to revolve. However, when the partial rotation to a new position has been accomplished, the clearance is greatly reduced so that the further rotation of the mold turning wheel properly aligns the locating blocks and thereby properly positions the mold disk for its forward bodily movement.

While, in general, this arrangement for intermittently rotating the mold disk between slug casting and ejecting positions and locating it in each position is satisfactory, it is, nevertheless, open to several objections. For one thing, considerable impact results when the gear segments initially come into driving contact with the driven bevel pinion, subjecting the parts to severe wear and strain even to the extent of

2

breakage at high speeds. A similarly objectionable impact results between the mold turning wheel and the locating block in arresting the mold disk in its operative positions.

The present invention eliminates these and other objectionable features by providing improved driving means for the mold disk with emphasis on reducing the impact between the driving and driven gear parts. More specifically, means are provided for imparting initial acceleration to the driven bevel pinion before the driving gear segment comes into contact therewith. Means are also provided to pre-position the mold disk to reduce the impact between the locating block and the mold turning wheel and, hence, to reduce the wear between the mold disk locking studs and banking blocks.

The present invention will allow operation of the machine at higher speeds, increase the span of life of the operating parts, reduce vibration, and result in less noisy operation.

In the accompanying drawings, the invention is shown merely in preferred form and by way of example, and obviously many changes and variations may be made therein and in its mode of adaptation which will still be comprised within its spirit. It is to be understood, therefore, that the invention is not limited to any form or embodiment except insofar as such limitations are specified in the claims.

Referring to the drawings:

Fig. 1 is a side elevation of a portion of a Linotype machine equipped with the present invention;

Fig. 2 is a rear view, partly in section, showing the driving mechanism for the mold disk just prior to operative engagement of a gear segment with the driven pinion;

Fig. 3 is a view similar to Fig. 2 but showing the parts in operative engagement;

Fig. 4 is a vertical section taken along the line 4—4 of Fig. 3, looking in the direction of the arrows;

Fig. 5 is a top view of the parts, showing the mold disk located and locked in one of its advanced positions;

Fig. 6 is a front elevation of the mold disk showing the operative mold in ejecting position and aligned with respect to the trimming knives;

and

Fig. 7 is a perspective view of one of the molds, showing its locking stud and the cooperating banking block on the vise frame.

The rotatable mold disk 1 is provided with a plurality of molds 2 (four as in the example

shown in Fig. 6), and is actuated in the usual manner by a driving pinion 3 meshing with the peripheral toothed portion 3^a of the disk. The pinion 3 is detachably connected to a shaft 5 so that it can be disconnected therefrom by the knob 4 and rotated by hand (when the machine is at rest) to bring any selected one of the molds 2 into use. At its rear end, the shaft 5 carries a small spur gear 6 which engages a larger spur gear 7 on a short jack shaft 8. At the rear end of the jack shaft 8, there is a small bevel pinion 9 and a steel block 10, the side plates of the latter being hardened and ground.

The power for rotating the mold disk 1 is supplied from the motor driven main cam shaft 11, the cams assembled thereon controlling most of the mechanical actions of the machine. The mold turning cam or wheel 12 is mounted on said shaft and carries on its circumference a long bevel gear segment 13 and a short bevel gear segment 14, the long segment being three times the length of the short segment. In each cycle of operation of the machine, the mold turning wheel 12 makes one complete clockwise rotation (as viewed in Fig. 1 of the drawings), enabling the short segment 14 to mesh with and drive the bevel pinion 9 in order to rotate the mold disk 1 through a one-quarter turn from ejecting to casting position, and similarly the long segment 13 to rotate the mold disk 1 through a three-quarter turn from casting back to ejecting position.

After the mold 2 in use has been brought into uppermost horizontal position for casting, the disk 1 is moved bodily forward and positioned exactly by the locking pins or studs 15 (see Figs. 5, 6 and 7) of the two inoperative vertically disposed molds, said studs 15 being adapted to enter a pair of banking blocks 16 on the vice frame 17 of the machine. While the mold disk is so positioned, molten metal is forced into the mold against the line of matrices for the casting of the slug. After casting, the mold disk is moved bodily backward to withdraw the locking studs 15 from the banking blocks 16, and the mold disk is then rotated through 270° to locate the mold with the contained slug in ejecting position, where once again the mold disk 1 is moved bodily forward to cause the locking studs 15 of the vertically disposed molds to enter the banking blocks 16. With the mold disk thus positioned, the slug is forced from the mold between a pair of trimming knives 18, as shown in Fig. 6. The mold disk is again moved bodily rearward to withdraw the locking studs from the banking blocks and remains at rest to await the beginning of the next cycle of operations.

As heretofore explained, in order to prevent wear on either the mold disk locking studs 15 or the banking blocks 16, it is necessary to locate the disk 1 as accurately as possible before its advancing movements. For this purpose, each of the gear segments 13 and 14 has immediately before and after it on the mold turning wheel 12 a hardened ground steel shoe 19 to cooperate with the square block 10. During rotation of the jack shaft 8 by the segments 13 and 14, ample clearance is provided for the turning of the square block 10, but after the segments 13 and 14 leave the bevel pinion 9, the mold disk 1 is immediately decelerated by the friction brake 20 acting on the shaft 5 and brought to a positive stop in the proper position by engagement of the steel shoe 19 with a side of the square block 10. With the mold disk 1 thusly prelocated, the studs 15 are

fairly accurately aligned with the banking blocks 16.

As thus far described, the parts, their construction and mode of operation are the same as in the commercial Linotype machines.

According to the present invention, and as best shown in Figs. 2, 3 and 4, identical steel plates 21, provided with the beveled faces 22, are attached to the rear face of the spur gear 7, said plates 21 being oppositely disposed and situated adjacent to the opposite sides of the square block 10, the operative one of said plates 21 being that shown at the right in the drawings. The outer edge 23 of the plate 21, which is close to the circumference of the spur gear 7, should be approximately straight and parallel to the respective operative side of the square block 10. Each of the gear segments 13 and 14 is provided at its foremost or leading end with a lug 24 and at its rearmost or following end with a lug 25, said lugs 24 and 25 projecting radially from the mold turning wheel 12.

As shown in Fig. 2, just before the teeth of the bevel gear segment (the short segment 14 being the one illustrated in the figure) run into active engagement with the teeth of the bevel pinion 9, the projecting lug 24 comes into glancing contact with the beveled face 22 of the plate 21 and imparts initial acceleration to the jack shaft 8 (see Fig. 3). The teeth of the bevel pinion 9 will, therefore, be in motion when engaged by the teeth of the driving segment, and the impact between the driving and driven teeth will thus be greatly reduced.

When the short gear segment 14 is supplying the driving motion, the jack shaft 8 will be rotated thereby through nearly 180°, bringing the leftwardly situated plate 21 into rightward or operative position. Now, when the teeth of the driving segment run out of active engagement with the teeth of the pinion 9, the latter will be quickly decelerated by the friction brake 20 (acting on the shaft 5), and the projecting lug 25 in vertical descent at this point will brush against the straight edge 23 and bring the latter into vertical alignment therewith to assure proper positioning of the mold disk, thereby reducing the impact between the cam shoe 19 and the square block 10.

When the long segment 13 is supplying the driving motion to the mold disk 1, the operation is precisely as described above except that (being three times longer than the short segment) it will rotate the jack shaft 8 through nearly 540°.

It is obvious that the operative surfaces of the plates 21 could be made integral with the spur gear 7, if desired.

As will be understood, the invention does not require the use of both gear segments 13 and 14, the two being shown as conventional.

What is claimed is:

1. In or for a typographical casting machine, mold disk driving mechanism comprising, in combination, a driving gear segment, a driven pinion, a bevelled element associated with the driven pinion, and a projection carried by the driving gear segment for contacting the bevelled element to impart initial acceleration to the driven pinion before the teeth of the gear segment and pinion come into engagement.
2. In or for a typographical casting machine, mold disk driving mechanism comprising, in combination, a driving gear segment, a driven shaft, a driven pinion mounted on said shaft, a bevelled element operatively carried by said

shaft, and a projecting lug carried by said gear segment for contacting said bevelled surface to impart initial acceleration to the driven shaft to reduce the impact between the teeth of the gear segment and the driven pinion.

3. In or for a typographical casting machine, mold disk driving mechanism comprising, in combination, a toothed driving segment, a toothed driven member, a bevelled element associated with the driven member, a projection carried by the driving member to engage the bevelled element to impart initial acceleration to the driven member, a straight-edged element associated with the driven member, and a second projection carried by the driving member to engage the straight-edged element in properly positioning the driven member in its operated position.

4. In or for a typographical casting machine, mold disk driving mechanism comprising, in combination, a driving gear segment, a driven shaft, a driven pinion mounted thereon, a bevelled plate operatively carried by the driven shaft, one side of said plate having a straight-edge, a projection carried by said driving segment for engaging the bevelled part of said plate to thereby impart acceleration to the driven shaft before the driving segment and the driven pinion come into driving engagement, and a second projection carried by the said driving segment for engaging the straight-edge portion of said plate in order to vertically align said straight-edge portion after operative engagement of the driving gear segment with the driven pinion.

5. In a typographical casting machine equipped with a power driven rotatable main cam shaft and a rotatable mold carrying disk, gear mechanism for rotating the mold disk periodically and

comprising, in combination, a driving gear segment mounted on and rotatable with the main cam shaft, a driven pinion connected to the mold disk, and means operated from the main shaft 5 and comprising a pair of momentarily engageable elements for initiating the rotation of the mold disk before the driving gear segment comes into meshing engagement with the driven pinion, one element being rotatable with the driving gear segment and the other element being rotatable with the driven pinion, and the two said elements making direct engagement with each other in initiating the rotation of the mold disk.

10 6. In or for a typographical casting machine, mold disk driving mechanism comprising, in combination, a driving gear segment, a driven shaft, a square faced block fixed to the driven shaft, a shoe carried by the driving gear segment to cooperate with said block in holding the driven shaft against rotation after the driving gear segment and the driven pinion run out of engagement, a straight-edged element associated with the driven pinion, and a projection carried by the 15 driving gear segment to engage the straight-edged element in advance of the engagement of the shoe with the square faced block.
